ATTORNEY.

UNITED STATES PATENT OFFICE.

THOMAS J. JONES, OF DALLAS, TEXAS.

PENCIL-VENDING MACHINE.

Application filed July 23, 1926. Serial No. 124,363.

This invention relates to coin controlled mechanism, and it particularly refers to that type of machine adapted to singly dispense small articles of merchandise such as 5 lead pencils, when a coin is deposited therein and upon movement of a convenient co-operating lever.

The principal object of the invention resides in the provision of a machine of the 10 character designated whose parts are of a durable nature, yet are so arranged as to enable minute adjustments to be made therein in order that the insertion of spurious coins or slugs will have no effect upon 15 the mechanism.

A further important object of the invention aims to provide as an improvement over previous machines of this character certain facilities by which the pencils contained therein are constantly maintained in a horizontal position and are not permitted to jam, and consequently hinder the delivery of a pencil when the proper coin is deposited.

25 With these and other objects and advantages in view, the invention has particular reference to its salient features of construction and arrangement of parts, by which the said objects are attained, and which will be enumerated and manifested in the following detail description and illustrated in the appended drawings, wherein,

Figure 1 is a direct front elevation of a machine constructed according to the present invention.

Figure 2 is the same machine reduced in size and in operative position.

Figure 3 is a sectional side elevational view on lines 3—3 of Figure 1, depicting the coin receiving and actuating mechanism.

Figure 4 is a similar view in which the cover plate of the coin receiving chute has been removed to more clearly show the associated parts.

Figure 5 is an enlarged view showing relative position of parts when ejecting a pencil, and

Figure 6 is a detail view of the coin moving parts.

Proceeding now more in detail with the drawings, in which similar characters of reference are used, 1 denotes the outer casing of the machine, having a cover 2 hinged at *a* and enclosing its front. The machine 55 ready for operation is disclosed clearly in Figure 2.

A skeleton partition 3 is provided in the machine, being fixed at *b*, continuing downward a short distance, as clearly illustrated in Figures 3 to 5, and directed rearwardly 60 on an angular plane to define a compartment 4, and turned abruptly downward to obtain a passage between the partition and the rear wall of the machine. Within this compartment 4 a supply of pencils 5 is maintained, and are constantly gravitated toward the rear of the machine by the inclined position of the shelf 6 formed by the angular disposition of the partition 3.

A plate 7 is pivoted at either side to a 70 pair of ears 8 depending from the inclined shelf 6, and is arranged, at each operation of the machine, to be pivoted upwardly as illustrated in Figure 5, to agitate the pencils, and to insure their proper distribution 75 into the passage intermediate the partition 3 and rear wall of the casing as shown. This plate however, due to the action of the coil spring 9 is held normally at the position shown in Figures 1, 3 and 4, its operation 80 will become more clear presently, as the description proceeds.

As particularly apparent in Figure 1, an operating handle 10 is located at a convenient position at the side of the casing 1, 85 upon preferably a squared shaft 11. This shaft continues through a projecting bracket 12 and a spacing sleeve 13 is applied thereon intermediate the bracket and casing side as in Figure 1. Upon the inner end of 90 the shaft 11, an arm 14 is affixed, which, in turn has pivoted at its end a link 15. This link pivotally engages the plate 7. Thus it will be seen that pressure upon the operating handle 10 will urge the plate upward 95 to engage and lift the volume of pencils resting upon the shelf 6.

The shaft 11 likewise carries a curved finger 16, which, upon each depression of the handle 10, is carried downward in the space 100 between the bracket 12 and a cover 17 affixed thereto, the latter being individually illustrated in Figure 6, and is spaced apart from the bracket by a strip 18, near the front of the machine.

Depending freely from a pivot 19, intermediate the bracket 12, and cover plate 17 is an arm 20, the lower end of which, as particularly apparent in Figures 1 to 5 swings within a slot 21 extending from *c* 110 to *d* in the shelf 22 below the bracket 12, and on which the latter rests. This shelf

is likewise connected to the lower end as is a curved receptacle 23 for the reception of coins.

The shelf 22 is punched at points spaced 5 from its either end to afford projections 24 to which is pivoted a pair of curved fingers 25. These fingers are arranged to co-act with a rocker plate 26, pivoted at its ends at 7 to the sides of the container 1. Since 10 the spring 9 previously referred to is connected both to the agitator plate 7, and to the rocker plate 26 co-operating action between these members is likewise obtained, but not until an interlocking medium such 15 as a coin, is inserted into the machine.

It will be observed that the rear wall of the machine is gradually curved inwardly at the base and to which the curved strips 27 are affixed to define a chute for reception 20 of ejected pencils.

In describing the operation of the machine and referring to some minor parts not mentioned previously, the pencils 5 are placed on the inclined shelf 6, and upon 25 tripping the handle 10, the agitator plate 7 is jiggled to assemble the pencils in relative longitudinal position in the passage intermediate the partition 3 and rear wall of the casing; the vertical ribs 28 restraining 30 the pencils against displacement. When in this position the pencils are supported upon the fingers 29 protruding from the rocker plate 23. The cover 2 is closed and locked at 30 and the machine is ready for operation.

It will be observed, that when the cover 2 is closed, the coin slot 31 therein, see Figure 2, is not directly in alignment with the coin chute intermediate the bracket 12 and cover plate 17, in which the coin falls. This 40 arrangement affords a measure of precaution against the insertion of a wire or other foreign object to trip the mechanism. The cover plate 17, it will be noted is supplied with a wing 32, against which the coin falls 45 when inserted in the slot 31, to guide the latter into the chute. The coin is indicated by the character 33 in Figures 4 and 5, and in the former figure is shown the position assumed by the coin immediately upon being 50 inserted into the chute, resting jointly upon the swinging arm 20 and spacer 18.

Now, upon forcing down the handle 10, the curved finger 16 travels downward and engages the coin on its edge, the result being 55 that the lower end of the swinging arm 20 is moved inward to a position where it engages the rocker plate 26 at 34, see Figure 5, pivoting this member as illustrated in Figure 5 to cause the integral fingers 29 to move 60 forward from beneath the column of pencils. Simultaneous with this movement, the small spring 35 connected to the curved fingers 25 forces the latter inward, and through positive adjustments, the ends of these fingers 65 engage beneath the column of pencils and

allow the ejection of only a single pencil. See Figure 5. These fingers are mounted independently of the rocker plate 26 but are held normally under tension of spring 35 merely by impinging the plate at a point 70 near their pivots at 24.

Upon completing the ejecting operation, the spring 9 returns the rocker plate 26 to its original position shown in Figure 3, and in so doing, the bottom of the latter impinges the lower parts of the fingers 25, overcoming the tension of the spring 35 to such an extent as to urge the fingers back to normal position, also shown in Figure 3.

A particularly important feature of the invention resides in its capability of being adjusted to overcome the action of counterfeit and spurious coins. In this regard, the spacing strip 18 may be increased or decreased in width according to the thickness 80 of the coin proposed to operate the machine, and further, the swinging arm 20 may be reduced or increased in width to gauge its swing according to the diameter of the proper coin. These adjustments may be of such 85 positive nature as to require that a substituted coin be precisely the same in dimensions as the proper coin before operation of the machine is insured.

It is obvious that some variation is possible in the machine as described in the foregoing, and it should be understood that it is not desired that the invention be limited to the specific disclosure set forth and that these mentioned variations may be resorted to, provided the same do not depart from the spirit or scope of the appended claims.

I claim:

1. In a check controlled apparatus a casing having an inclined merchandise support 105 therein, an operating handle and shaft; a check chute; a curved finger carried by said shaft, and arranged to move in said chute, an arm pivoted also in said chute; an agitator plate controllable by said operating handle; a merchandise releasing means; means for receiving and holding a check within said chute preparatory to its engagement by said curved finger when said handle is operated, said check and check holding means to cause pivotal movement of said merchandise releasing means, and means co-operable with said merchandise releasing means to retain said merchandise during 110 ejecting operation of said releasing means. 115

2. In a check controlled vending apparatus, a casing having an inclined merchandise support therein, an agitator plate having pivotal movement with respect to said support, a merchandise releasing means having a common tensioning means with said agitator plate, a check receiving chute; a shaft extending through said chute, a curved finger carried by said shaft; a pivoted arm depending below said curved finger; means 120

125

130

- to hold a check deposited in said chute against said pivoted arm, means to revolve said shaft to engage said curved finger against the said check and thereby move 5 said pivoted arm to impinge and actuate said merchandise releasing means, and means to hold said merchandise during operation of said releasing means.
3. In a check controlled vending apparatus; a casing having an inclined merchandise support therein; an agitator plate having pivotal movement with respect to said support; a check receiving chute; a rotatable shaft extending through said chute and having operable engagement with said agitator plate; a curved finger carried by said shaft; a merchandise releasing member having a joint tensioning means with said agitator plate; a pivoted arm mounted within said 10 check receiving chute, and arranged for engagement with said merchandise releasing member; means to hold a check in a position to be urged against said pivoted arm by said curved finger when said shaft is rotated, to effect movement of said releasing member, and means to hold said merchandise in check during operation of said releasing member.
4. In a check controlled vending machine; a casing having a merchandise support therein; a merchandise agitating plate movably mounted with respect to said support; a check receiving chute; a rotatable shaft extending through said chute and operatively connected with said agitator plate; a merchandise releasing member having joint tensioning means with said agitator plate; a pivoted arm depending within said 15 chute and arranged for swinging engagement with said merchandise releasing mem-
- ber; means carried by said shaft to urge an interlocking check against said depending arm to trip said merchandise releasing member; and means to hold said merchandise in check during actuation of said 45 releasing member.
5. In a check controlled vending apparatus; a casing, a merchandise receptacle within said casing, an agitating member, a check chute, a rotatable shaft extending through the side of said casing and having operable engagement with said agitating member; a check engaging finger carried by said shaft; a merchandise releasing member; means for holding said member normally 50 beneath said merchandise; means depending within said chute to engage and trip said merchandise releasing means when a check is urged thereagainst by rotation of said shaft and check engaging finger, and means co-operable with said merchandise releasing member to retain said merchandise during operation of said merchandise releasing member.
6. A check controlled vending apparatus; a check chute; an agitating member; a shaft carrying an operating handle and having operable connection with said agitating member; a merchandise releasing plate having spring engagement with said agitating 55 member; a pivoted arm depending within said check chute; means carried by said shaft to urge a check deposited in said chute against said depending arm to trip said merchandise releasing plate, and means co-operable with said plate to suspend said merchandise during operation of said releasing plate.

In testimony whereof I affix my signature.

THOMAS J. JONES
